Hezekiah Conant

United States Patent Office.

HEZEKIAH CONANT, OF PAWTUCKET, RHODE ISLAND.

Design No. 3,949, dated April 5, 1870.

DESIGN FOR SPOOLS FOR THREAD.

The Schedule referred to in these Letters Patent and making part of the same.

To all whom it may concern:

Be it known that I, HEZEKIAH CONANT, of Pawtucket, in the county of Providence and State of Rhode Island, have originated and designed a new Design for Embossing the Ends of Sewing-Thread Spools; and I do hereby declare that the following specification is a full, clear, and exact description of the same, reference being had to the drawings making a part of this specification.

The purpose of the design shown in the drawings is to preserve the number of the thread with which the spool is wound, after the label has been destroyed by the act of setting the spool upon the spool-stand of a sewing-machine.

Near the outer edge of the head of the spool is em-

bossed in the wood an endless chain of loops, *a a*, formed apparently by arranging two threads so as to cross each other at regular distances. In the eye of the loop the number of the thread is stamped.

What I claim as my invention, and desire to secure by Letters Patent, is—

The design for ornamenting the ends of sewing-thread spools, which consists in a chain of loops, *a a*, within which loops is a number, expressive of the number of the thread wound on the spool, substantially as shown and described.

HEZEKIAH CONANT.
